(57) **CLAIM**

An ornamental design for a cleaning mitt, as shown and described.

DESCRIPTION

FIG. 1 is a front view of a cleaning mitt, in accordance with the present invention;

FIG. 2 is a rear view of the cleaning mitt of FIG. 1;

FIG. 3 is a left side view of the cleaning mitt of FIG. 1;

FIG. 4 is a right view of the cleaning mitt of FIG. 1;

FIG. 5 is a top view of the cleaning mitt of FIG. 1;

FIG. 6 is a bottom view of the cleaning mitt of FIG. 1;

FIG. 7 is a perspective view of the cleaning mitt of FIG. 1;

FIG. 8 is a cross-sectional view of the cleaning mitt of FIG. 5; and,

FIG. 9 is a cross-sectional view of the cleaning mitt of FIG. 5.

In the drawings, the broken lines illustrate environment and form no part of the claimed design.
